UNITED STATES PATENT OFFICE.

WILLIAM B. PIERCE AND FRANK M. PIERCE, OF CHICAGO, ILLINOIS, ASSIGNEES TO
PIERCE WRAPPING MACHINE COMPANY, OF CHICAGO, ILLINOIS, A CORPORATION
OF ILLINOIS.

PAPER-FOLDER.

1,237,812.

Specification of Letters Patent. Patented Aug. 21, 1917.

Application filed January 2, 1915. Serial No. 304.

To all whom it may concern:

Be it known that we, WILLIAM B. PIERCE and FRANK M. PIERCE, citizens of the United States, and residents of the city of Chicago, in the county of Cook and State of Illinois, have invented certain new and useful Improvements in Paper-Folders; and we do hereby declare that the following is a full, clear, and exact description of the 10 same, reference being had to the accompanying drawings, and to the numerals of reference marked thereon, which form a part of this specification.

This invention relates to an improved 15 type of folder device for folding paper or any material used to wrap an article or in any other similar operation wherein a folder device is required. This device is well adapted for use upon the revolving paper 20 carrying shuttle used in high speed wrapping machines wherein a continuous wrapping strip is applied around an article. In a wrapping machine adapted to wrap articles of different size and shape the relation of the article to the revolving shuttle 25 is not always the same, and consequently it is necessary to provide a mechanism from which the strip is drawn for application to the article which will automatically adapt 30 itself to different conditions for wrapping, so that there will be no possibility of resistance to the passage of the paper which might result in tearing the same.

It is an object therefore of this invention 35 to construct a folder device for the shuttle of a wrapping machine adapted to feed the wrapping material drawn therethrough to create a fold therein, and adjustable so as to properly direct the material drawn therefrom toward the article being wrapped.

It is also an object of this invention to 40 construct a folder device a part of which co-acts with another member to afford a tension mechanism for the paper as it is led into the folder device for folding.

It is furthermore an important object of 45 this invention to construct a folder device for connection to the paper carrying shuttle of a wrapping machine and mounted upon 50 the shuttle in a manner to permit movement of the folder device in different directions to permit the paper to be properly directed to different articles wrapped by the machine.

It is finally an object of this invention to 55 construct an improved form of folder device having a long resilient integral extension by which the same is connected to a shuttle of a wrapping machine, thus permitting the folder device to assume various positions when in operation to properly lead the wrapping material to the article being wrapped.

The invention (in a preferred form) is illustrated in the drawings and hereinafter 60 more fully described.

In the drawings:

Figure 1 is a central vertical section taken through a shuttle illustrating a device embodying the principles of our invention connected thereto and shown in elevation.

Fig. 2 is a fragmentary enlarged detail view of a portion of the shuttle shown with the folder connected thereon.

Fig. 3 is a view taken on line 3—3 of Fig. 1.

Fig. 4 is a detail section taken on line 4—4 of Fig. 1.

Fig. 5 is a detail section taken on line 5—5 of Fig. 2.

Fig. 6 is a detail section taken on line 6—6 of Fig. 2.

Fig. 7 is a detail section taken on line 7—7 of Fig. 3, with parts omitted.

As shown in the drawings:

The shuttle shown in Fig. 1, consists of sections 1 and 2, pivotally connected to one another by means of a pintle bolt 3, and each provided with hinged peripheral walls 4, adapted to be locked to one another by locking mechanism 5, said hinged walls when opened affording access to the interior of the shuttle for the insertion of folded wrapping material 6, therein. A pair of rollers 7, are journaled on each side of an opening in the inner peripheral wall of the section 2, and a strip of paper X, is drawn therethrough from the inner fold of the wrapping material, thence around a suitable tension mechanism 8, and finally 100 down and around a spring plate 9, secured at one of its ends in a compartment 10, of the shuttle section 2. A pintle bolt 11, is secured transversely within the compartment 10, in the side walls of the shuttle, and engaged thereon is a U-shaped construction comprising the resilient plate extension 12, which is integrally connected through

22 curved member 13, with the inlet plate member 14, of a folder nozzle. Said folder nozzle consists of an outer plate 15, integral with said inner plate 14, along the lower portion thereof, with said respective plates 14 and 15, converging toward one another at the exit end of the nozzle, and with a lip 16, flaring outwardly and tapering toward the exit end of the nozzle formed integral 19 with the upper portion of the plate 15, and curved over the upper edge of the inner plate 14. Also secured transversely within the compartment 10, between the side walls of the shuttle section is a pintle bolt 17, on 15 which is journaled a convex surfaced roller 18, against which the inner surface of the plate member 12, bears at all times, and as clearly shown in Figs. 1 and 2, said spring plate 9, bears at its free end against the outer surface of said plate member 12, to hold the folder device over and against said roller 18.

25 A locking mechanism for the respective shuttle sections 1 and 2, is provided, consisting of a latch bolt 19, mounted on a pivot 20, in the shuttle compartment 10, adapted to engage through registering apertures in abutting walls 21 and 22, of the respective sections 1 and 2, to hold the same connected 30 one to another. A leaf spring 23, is secured at one of its ends within said shuttle compartment 10, and at its other end bears against the tail of said latching bolt 19, to normally impel the same into locking position.

35 The operation is as follows:

The paper strip X, is drawn from within the shuttle around one of the idler rollers 7, through the tension mechanism 8, and 40 thence between the spring plate 9, and resilient plate 12, of the folder device, the friction exerted thereby on the paper as the same passes therebetween serving as a secondary tension mechanism for that portion 45 of the paper immediately passing into the folder nozzle.

Due to the many different sizes and shapes of articles capable of being wrapped by the revolution of a shuttle therearound, it is 50 obvious that the relative position and angle of feed of the paper to the article varies according to the size and position of the article. It is essential, however, that the paper be permitted to pass easily to the article regardless of the fluctuations in relative positions between the shuttle and the article being wrapped, which are inherent in a high speed machine. This is most efficiently taken care of by the folder nozzle, 55 due to the fact that it is pivotally mounted upon the pintle 11, on a long resilient shank extension 12, so that said nozzle is permitted to swing transversely of the shuttle as well as in a plane parallel to the plane of the

shuttle. Any intermediate warping movement imposed upon the nozzle readily takes place due to the convex surface of the roller 18, against which the extension of the folder nozzle is pressed by the resilient plate 9, said roller acting merely as a stop for movement 65 of the folder tension plates in one direction, about the pivot 11. It is apparent, therefore, that through certain degrees of movement the folder nozzle can assume practically any angle and position, so that the wrapping material fed around the rounded extension 15, and into the nozzle is led easily to the material being wrapped, meanwhile receiving a fold created therein by the folding nozzle and permitting easy and proper 70 application of the folded strip to the article without possibility of tearing.

We are aware that various details of construction may be varied through a wide range without departing from the principles 85 of this invention, and we therefore do not purpose limiting the patent granted otherwise than necessitated by the prior art.

We claim as our invention:

1. In a device of the class described, a 90 folder nozzle, a curved resilient U-shaped plate integral therewith, acting as a tension device for paper drawn therearound and a pintle on which the end of said plate is connected.

2. In a device of the class described the combination with a folder nozzle and a resilient mounting therefor, of a resilient plate bearing thereagainst affording a tension mechanism for paper drawn therebetween. 100

3. In a device of the class described, a pivotally mounted folder nozzle comprising plate members arranged in converging relation, a lip formed on one thereof and folded over the other, a long resilient plate extension integral with one of said plate members of the nozzle by which said folder device is pivotally mounted, resilient means bearing against said plate extension on one side thereof, and a convex roller disposed on the other side thereof serving as a stop therefor. 105

4. In a device of the class described, a folder nozzle, a long resilient curved extension integral therewith, pivotal connections therefor to a shuttle on which the device is mounted, resilient means bearing against said extension between which the paper is drawn and led to said nozzle serving as a tension means for said paper, and a convex roller acting as a stop for the associated nozzle and plate extension to resist stress exerted thereon by said resilient member. 115

5. In a folder and tension device for a shuttle, a folder nozzle, a resilient extension integral therewith and pivotally connected to said shuttle, a resilient plate member secured on said shuttle and bearing against

said extension, and means acting to limit movement of said associated nozzle and plate extension.

6. In a folder device of the class described embracing a folder nozzle, a resilient integral extension integral therewith bent around and substantially parallel to said nozzle from the entrance end thereof, and means bearing thereagainst to confine a strip of wrapping material thereto being led to said nozzle and serving as a tension mechanism therefor.

7. In a device of the class described for attachment on a shuttle, a folder nozzle acting to tension paper led therearound, and means for mounting the same on the shuttle to permit the nozzle to swing transversely of and in a plane parallel to the plane of the shuttle.

8. In a device of the class described, folder means, mechanism bearing thereagainst and co-acting therewith to afford a tension device, and means acting as a stop for said folder means to resist stress exerted thereon by said mechanism.

9. In a device for use in a wrapping machine, a spring plate, a convex roller, a folder nozzle, and a resilient extension integral therewith and curved to extend between

said spring plate and roller to afford a 30 hinged mechanism for guiding and folding wrapping paper.

10. In a device of the class described, a pivoted folding member, tension means for material led to said member bearing against 35 said member, and a rotary stop to limit the pivotal movement of said member.

11. In a wrapping machine of the class described, a movable folder nozzle, a resilient plate bearing thereagainst affording 40 a tension mechanism for wrapping paper, and a rotary stop to limit the movement of said nozzle.

12. In a device of the class described, a folder nozzle, a resilient extension integral 45 therewith, means engaging the end thereof to permit pivotal movement of the nozzle, resilient tension means bearing against said extension, and means acting to limit the movement of said nozzle.

In testimony whereof we have hereunto subscribed our names in the presence of two subscribing witnesses.
